[57] ABSTRACT

[22] Filed: Apr. 17, 1974

A power press is provided with an assembly of relatively rotatable embossing rings and with a control system for rotating the rings and for reciprocating the press ram in timed relation to each other. The control system comprises a power driven rotary shaft; selectively engagable and disengagable drive transmitting connections between the shaft and the embossing rings, and an electrical circuit including switches which are closed and opened in predetermined sequence by rotation of the shaft, whereby the embossing rings are rotated step by step in predetermined order and the press ram is moved into and out of an embossing position during time intervals between successive steps of ring rotation.

EMBOSSING PRESS

BACKGROUND OF THE INVENTION

The invention relates to power presses, and it is concerned more particularly with a power press for embossing multi-digit serial numbers successively in consecutive order upon a strip of sheet stock which is advanced step by step through the press.

Power presses of the above mentioned type have heretofore been developed and have been specifically adapted for the manufacture of automobile license plates. In such serial number embossing presses as heretofore developed an assembly of relatively rotatable embossing discs and a reciprocable embossing ram have been arranged in cooperative relation to each other, and provisions have been made for turning the embossing discs and for reciprocating the embossing ram sequentially in timed relation to each other. To that end, an indexing mechanism has been provided which was operable to turn the embossing discs step by step in predetermined order and which was operatively interrelated with the embossing ram in such a manner that a disc turning operation of the indexing mechanism was initiated by an upstroke of the ram from an embossing position, and so that a down stroke of the ram would bring it into an embossing position while the discs are held in indexed positions.

For mass production purposes, it is desirable to complete the embossing operations in extremely rapid succession, as for instance at the rate of 80 or more embossing operations per minute. However, such fast operation of an embossing press, and particularly of an embossing press for the manufacture of automobile license plates presents certain difficulties. In order to perform the embossing operation within a very short time, that is, in a second or less, the embossing stroke of the press ram will first of all have to be reduced to the required minimum which ordinarily will be less than $\frac{1}{2}$ inch. Then, the indexing mechanism must be operable at a high speed and with utmost precision which again involves inertia problems and difficulties in timing the indexing mechanism and the short ram strokes relative to each other. Further, the ram pressures for embossing sheet metal such as is normally used for automobile license plates are considerably higher than those for ordinary punching process and the various components of the embossing press and of the indexing mechanism must therefore be sturdily constructed and be able to stand up and function reliably under severe operating conditions and without undue wear.

U.S. Pat. application Ser. No. 296,602, filed on Oct. 11, 1972 by Donald R. Alexander for Serial Number Embossing Apparatus, now U.S. Pat. No. 3,824,921 issued July 23, 1974, discloses an embossing press for use in the manufacture of automobile license plates, and the embossing press disclosed in the present application involves features of improvement over the press disclosed in the mentioned earlier application.

SUMMARY OF THE INVENTION

Generally, the present invention provides an improved power press which may be operated at relatively high speeds to emboss multi-digit serial numbers successively in consecutive order upon a strip of sheet stock which is advanced step by step through the press.

More specifically, the invention provides an embossing press of the mentioned character which incorporates an assembly of relatively rotatable embossing rings and an improved control system for rotating the embossing rings and reciprocating the press ram in times relation to each other.

The improved control system as contemplated by the invention incorporates a power driven indexing mechanism for the embossing rings, which is operatively interrelated with the operating mechanism for the embossing ram of the press in such a manner that an actuating signal for the press is emitted by operation of the indexing mechanism. In this respect the embossing press incorporating the present invention differs from the embossing press of the mentioned earlier application wherein an actuating signal for a power driven indexing mechanism is emitted by operation of the embossing ram.

The present invention further provides an improved serial number embossing press of the mentioned character wherein selectively engagable and disengagable clutch units are operatively interposed between an assembly of relatively rotatable embossing rings and an oscillating indexing arm, and wherein the clutch units are electrically controlled so as to rotate the embossing rings step by step in predetermined order by the oscillating indexing arm.

The invention further provides an improved serial number embossing press of the mentioned character wherein selectively engagable and disengagable lock units are operatively interposed between an assembly of relatively rotatable embossing rings and a stationary mounting structure for the rings, and wherein the lock units are electrically controlled so that the rings are positively secured against turning during the embossing operation, and so that the rings are selectively released for turning by the oscillating indexing arm.

The invention also provides an improved serial number embossing press incorporating an improved drive mechanism for an oscillating indexing arm whereby the indexing arm is steadily accelerated and decelerated without setting up objectionable inertia forces.

The improved embossing press provided by the present invention also includes provisions for turning the decimal rings either step by step in predetermined order, or for turning any selected one of the decimal rings individually step by step independently of the others. Such provisions are of particular advantage for the production of automobile license plates where it may be desirable to terminate a production run short of the maximum available numbering range, and wherein a new production run is to be started with a serial number configuration other than that at which the previous production run was terminated.

THE DRAWINGS

The foregoing and other features and advantages of the invention will become more fully apparent as this disclosure proceeds with reference to the accompanying drawings, wherein

FIG. 1 is a perspective front view of an embossing press embodying the invention;

FIG. 2 is a perspective view similar to FIG. 1 but showing the press in a different condition of adjustment;

FIG. 3 is a side view of the press shown in FIG. 2; FIG. 4 is a partial top view on line 4-4 of FIG. 3;

FIG. 5 is a view similar to FIG. 4 but showing parts in a different condition of adjustment;

FIG. 6 is an enlarged elevational view on line 6—6 of FIG. 4;

FIG. 7 is a top view similar to FIG. 4 but with parts omitted to expose structure hidden in FIG. 4;

FIG. 8 is an enlarged view of part of FIG. 7;

FIG. 9 is a section on line 9—9 of FIG. 8;

FIG. 10 is an enlarged elevational view partly in section on line 10—10 of FIG. 5;

FIG. 11 is a section on line 11—11 of FIG. 10;

FIG. 12 is an enlarged detail view, partly in section, on line 12—12 of FIG. 7;

FIG. 13 is a view, partly in section on line 13—13 of FIG. 12;

FIG. 14 is an elevational view on line 14—14 of FIG. 7;

FIG. 15 is a top view of FIG. 14;

FIG. 16 is an elevational view, partly in section, on line 16—16 of FIG. 14;

FIG. 17 is a perspective diagram of a pneumatic circuit and associated parts for controlling the embossing press shown in FIGS. 1—16;

FIGS. 18 and 19 are operating diagrams corresponding, respectively, to FIGS. 4 and 5; and

FIG. 20 is a diagram of an electrical control circuit and associated parts for operating the embossing press shown in FIGS. 1—16.

DETAILED DESCRIPTION

The basic component of the embossing press shown in FIG. 1 is a hydraulic press 1 of generally conventional construction, and more specifically of the type shown in U.S. Pat. No. 2,927,558 issued on Mar. 8, 1960 to R. Smilges for "Hydraulic Press and Control Means." Briefly, the press 1 comprises a main frame 2 of the open gap or C type; a reciprocating ram 3, and a hydraulic power unit 4 (FIG. 19) within a hollow upper part of the frame 2. Also enclosed within the hollow upper part of the C frame 2 are an electric motor 6, a pump 7, and a belt drive 8 connecting the motor with the pump. The hydraulic power unit 4 includes an internal hydraulic circuit which is supplied with pressure fluid by the pump 7 and which is controlled by a solenoid valve 9. When the coil of the solenoid valve is energized, hydraulic pressure builds up within the power unit 4 and forces the ram 3 down on an embossing stroke, and when the solenoid coil is subsequently de-energized the ram 4 moves automatically from its lowered embossing position (FIG. 19) to a raised non-embossing position (FIG. 18).

The press frame 2 (FIG. 1) is provided at the bottom of its C-gap with an extension frame generally designated by the reference character 101. The extension frame 101 comprises a pair of side beams 11 and 12, a front cross beam 13, and a pair of front supporting legs 14 and 16. The rear ends of the side beams 11 and 12 are rigidly secured to opposite side portions of the press frame 2, and the front legs 14 and 16 sustain the beam assembly 11, 12 and 13 in a horizontal position. Slideably mounted on the side beams 11 and 12 of the extension frame 101 for horizontal back and forth movement relative to the press frame 2 is a subframe 102, and operatively mounted on the subframe 102 is a numerical registering device comprising a concentric radial assembly of four decimal rings W, X, Y and Z, an oscillating indexing arm 103, and a drive mechanism

for the indexing arm, generally designated by the reference character 104 (FIG. 6). A rack and pinion drive 105 (FIG. 3) is operable by a hand wheel 106 to shift the subframe 102 back and forth between the positions in which it is shown in FIGS. 1 and 2.

In FIG. 7, the subframe 102 is shown without the decimal rings to expose an anvil 107 and two radial support rails 108 and 109 which are secured in fixed positions on a platform 173 of the subframe 102 and on which the concentric decimal rings W, X, Y and Z are supported in rotatable relation to each other. Each of the decimal rings has a circular groove (FIG. 9) at its under side, and these grooves are engaged by guide rollers 111 on the anvil 107, and by corresponding guide rollers 112 and 113 on the support rails 108 and 109, respectively, to keep the rings centered on a common axis. Radial hold-down rollers 114 and 116 (FIG. 4) are suitably mounted on the subframe 102 in contact with the upper sides of the decimal rings to prevent upward separation of the rings W, X, Y, Z from the guide rollers 111, 112 and 113.

The indexing arm 103 (FIG. 10) has a hub sleeve 117 and a bracket end 118 extending radially outwardly from the sleeve 117 below the decimal rings W, X, Y, Z. Conical roller bearings 119 and 121 mount the arm 103 on a king pin 122 which is flanged to the subframe by cap screws 123 and extends axially of the rings W, X, Y, Z on the common axis of the latter.

The drive mechanism 104 for oscillating the indexing arm 103 about the axis of the king pin 122 is best shown in FIGS. 6, 7 and 17. It comprises an electric motor 124, a speed reduction unit 126 connected to the motor 124 and having a rotary output shaft 127; a counter shaft 128 mounted on the subframe 102 in bearings 129 and 131 (FIG. 6) for rotation on an axis extending parallel to and spaced radially from the axis of the king pin 122. A pulley 132 (FIG. 17) on the output shaft 127 of the speed reduction unit 126 is connected by a belt 133 with a sheave 134 which is keyed to the counter shaft 128. The transmission ratio between the motor 124 and the counter shaft 128 is so proportioned that the counter shaft 128 rotates in the direction of arrow 138 at a speed which is substantially lower than the armature speed of electric motor 124, a suitable speed for the counter shaft 128 being, for instance, 80 RPM. A disc 137 (FIG. 17) is keyed to the shaft 128 for rotation therewith on substantially the same level as the bracket end 118 of the indexing arm 103. The disc 137 (FIG. 7) mounts an eccentric pin 138, and a connecting rod 139 is pivotally connected at one end to the pin 138 and at the other end to a wrist pin 141 (FIG. 6) on the indexing arm 103.

The radial spacing of the eccentric pin 138 (FIG. 7) from the axis of the counter shaft 128, and the radial spacing of the wrist pin 141 from the axis of the king pin 122 are so proportioned that a 360° turn of the disc 137 swings the indexing arm 103 in forward and rearward directions about its pivot axis on the king pin 122 through angular range of 36°.

FIGS. 4, 7, 17 and 18 show the dead center position of the connecting rod 139 which places the indexing arm 103 at one end of its 36° swinging range, and FIGS. 5 and 19 show the other dead center position of the connecting rod 139 which places the indexing arm 103 at the other end of its 36° swinging range.

A forward stroke of the indexing arm 103 from the FIG. 4 position to the FIG. 5 position will take place

upon a 180° clockwise turn of the disc 137 from its FIG. 18 position to its FIG. 19 position; and a further 180° clockwise turn of the disc will subject the indexing arm 103 to a return stroke from its FIG. 5 position to its FIG. 4 position. The electric motor 124 drives the disc 137 at constant angular velocity, and during the first 180° clockwise turn of the disc 137, the indexing arm will be gradually accelerated from standstill to maximum angular velocity, and it will then be gradually decelerated to momentary standstill at the end of the forward stroke. During the next 180° clockwise turn of the disc 137 the indexing arm will again be gradually accelerated from standstill at the beginning of the return stroke to maximum angular velocity and during the second half of the return stroke, it will again be decelerated to standstill at the end of the return stroke.

In FIG. 18, the dash dotted line 142 designated the radial position to which the indexing arm 103 is swung by a 165° clockwise turn of the eccentric pin 138, and the dash-dotted line 143 designates the radial position to which the indexing arm is swung by a 180° clockwise turn of the eccentric pin 138. A short time interval is therefore provided during which the indexing arm remains almost at standstill at the end of its forward stroke while the counter shaft 128 continues to rotate at constant angular velocity. The same explanations apply to FIG. 19 where the dash dotted line 144 designates the radial position to which the indexing arm is swung by a 165° clockwise turn of the eccentric pin 138, and the dash dotted line 146 designates the radial position to which the indexing arm is swung by a 180° turn of the eccentric pin 138. Another short time interval is therefore provided during which the indexing arm remains almost at standstill at the end of its return stroke while the counter shaft 128 continues to rotate at constant angular velocity.

As will presently be explained in detail, driving connections between the indexing arm and the decimal rings, and locking connections between the decimal rings and the subframe are automatically established and interrupted during the short time intervals at which the indexing arm remains almost at standstill while the counter shaft continues to rotate at constant angular velocity. If, as mentioned previously, the counter shaft rotates at 80 RPM, only small fractions of a second will of course be available for the establishment and interruption of the mentioned driving and locking connections.

As shown in FIG. 10, a bank of four clutch units W-1, X-1, Y-1 and Z-1 are mounted on the bracket end 118 of the indexing arm below the decimal rings W, X, Y, Z, respectively. The clutch unit X-1 provides an engagable and disengagable torque transmitting connection between the indexing arm 103 and the decimal ring X by means of a reciprocable clutch pin 147 (FIG. 11) which is connected to the piston rod 148 of a pneumatic cylinder 149. Cap screws 151 secure the cylinder 149 to the underside of the end bracket 118, and hose lines 152 and 153 lead into the cylinder above and below the piston 154 therein. A guide bushing 156 (FIG. 11) for the clutch pin 147 is secured axially within the end bracket 118, and the upper end of the clutch pin 147 is tapered for axial entry into anyone of a circular series of 10 equally spaced holes 157 in the decimal ring X.

The foregoing explanations of the clutch unit X-1 analogously apply to the clutch units W-1, Y-1 and

Z-1, which comprise clutch pins 158, 159, 160, respectively (FIG. 7) and are operable by associated pneumatic cylinders each having a pair of hose lines 152 and 153. The decimal ring W (FIG. 10) has a circular series of 10 equally spaced clutch pin receiving holes 161; the decimal ring Y has a circular series of ten equally spaced clutch pin receiving holes 162; and the decimal ring Z has a circular series of 10 equally spaced clutch pin receiving holes 163, all of these clutch pin receiving holes being each lined with a bushing 164 as shown in FIG. 10.

During each return stroke of the indexing arm from its FIG. 5 position to the position which is indicated in FIG. 19 by the dash-dotted line 144, all of the clutch units W-1, X-1, Y-1 and Z-1 are kept in disengaged condition by air pressure admitted to their respective pneumatic cylinders through the upper hose lines 152 (FIG. 11), as will be explained more fully hereinbelow. At the same time all the decimal rings are secured 20 against rotation from their indexed positions by means of four lock units W-2, X-2, Y-2, and Z-2 (FIG. 12) which are mounted on the subframe 102 in the space between the anvil block 107 (FIG. 7) and the ring support rail 109.

25 The lock units W-2, X-2, Y-2 and Z-2 are substantially duplicates of the clutch units W-1, X-1, Y-1 and Z-1. The lock unit W-2 provides an engagable and disengagable locking connection between the subframe 102 and the decimal ring W, and the lock units X-2, 30 Y-2 and Z-2 similarly provide engagable and disengagable locking connections between the subframe 102 and the decimal rings X, Y and Z, respectively. The lock unit W-2 comprises a reciprocable locking bolt 158' (FIG. 13) which is connected to the piston rod 167 of a pneumatic cylinder 168. Cap screws 169 secure the cylinder 168 to a mounting block 171 which in turn is secured by cap screws 172 to a platform 173 of the subframe 102. Hose lines 152' and 153' lead into the cylinder 168 above and below a piston 176 therein. 40 A guide bushing 177 (FIG. 13) for the lock bolt 158' is secured in the mounting block 171 and the upper end of the lock bolt 158' is tapered for axial entry into any one of the holes 161 of the decimal ring W.

45 The foregoing explanations of the lock unit W-2 similarly apply to each of the lock units X-2, Y-2, Z-2. A lock bolt 147' (FIG. 12) of the lock unit X-2 is shiftable axially into and out of any of the clutch pin receiving holes 157 of the decimal ring X; a lock bolt 159' is shiftable axially into and out of any of the clutch pin receiving holes 162 of the decimal ring Y; and a lock bolt 160' is shiftable axially into and out of any of the clutch pin receiving holes 163 of the decimal ring Z.

The mounting block 171 (FIG. 7) for the lock units 50 W-2, X-2, Y-2 and Z-2 is secured on the subframe 102 in such a position that the lock bolts 158', 147', 159' and 160' will register with overlying clutch pin receiving holes of the decimal rings W, X, Y, Z, respectively, whenever the indexing arm is in position at the end of a forward stroke (FIGS. 5 and 19).

60 FIG. 17 is a simplified diagrammatic showing of a pneumatic control system for the clutch units W-1, X-1, Y-1, Z-1 and for the lock units W-2, X-2, Y-2 and Z-2. The indexing arm 103 is shown in FIG. 17 as in FIG. 18, in the starting position for a forward stroke; the clutch pins on the indexing arm are in retracted positions except the clutch pin 158 of the W-1 unit which is in its projected ring W engaging position; and the

lock bolts on the subframe are in their projected ring locking positions except the lock bolt 158' which is in its retracted ring W unlocking position. A bank of four solenoid valves W-3, X-3, Y-3 and Z-3 are mounted in fixed positions on the subframe, each valve having two solenoid coils which may be alternately energized by an electrical control circuit as shown in FIG. 20 and which will be discussed more fully hereinbelow.

The solenoid valve W-3 has an air inlet port, an air outlet, and a shiftable valve body, not shown, which in one position, when the solenoid coil S1A is energized, connects the inlet and outlet ports with conduit lines 181 and 182, respectively; and which in another position, when the solenoid coil S1B is energized, connects the inlet and outlet ports with the conduit lines 182 and 181, respectively. The same explanations apply to the solenoid valves X-3, Y-3 and Z-3. A manifold 183 connects a source of air pressure 184 with the inlet ports of the valves W-3, X-3, Y-3 and Z-3.

The conduit line 181 of the valve W-3 branches into the hose lines 152 and 153' of the clutch and lock units W-1 and W-2, respectively, and the conduit line 182 of the valve W-3 branches into the hose lines 153 and 152' of the clutch and lock units W-1 and W-2, respectively. Accordingly, admission of air pressure to the conduit line 182, as shown in FIG. 17, projects the clutch pin 158 and simultaneously retracts the lock bolt 158'; and admission of air pressure to the conduit line 181 would retract the clutch pin 158 and simultaneously project the lock bolt 158'. In other words, the clutch and lock units W-1 and W-2 are interconnected for seesaw operation, that is, when the clutch pin is up the lock bolt is down, and vice versa.

The foregoing explanations of the clutch unit W-1, the lock unit W-2 and valve unit W-3 are equally applicable to the X-1, X-2, X-3 units, and also to the Y-1, Y-2, Y-3 units, and to the Z-1, Z-2, and Z-3 units. The clutch unit X-1 and its associated lock unit X-2, as well as the clutch unit Y-1 and its associated lock unit Y-2, and the clutch unit Z-1 and its associated lock unit Z-2 are operable seesaw fashion the same as the clutch unit W-1 and its associated lock unit W-2.

As shown in FIGS. 4, 5 and 9, each of the decimal rings W, X, Y, Z is provided at its obverse side with a circular series of raised embossing digits 0 to 9 at 36° circular spacings from each other. The embossing station of the registering device is designated in FIG. 4 by the radial line R, and in the condition of the device as shown in FIG. 4 the ciphers of all rings are radially aligned so that the digit configuration will be 0-000.

A change from the 0-000 digit configuration of FIG. 4 to the 0-001 digit configuration of FIG. 5 is effected as follows. In the FIG. 4 condition of the device, the W ring is coupled to the indexing arm by the projected clutch pin 158 (FIG. 17); the remaining clutch pins are retracted; and all rings are locked by the projected lock bolts except the ring W which is unlocked due to the retraction of lock bolt 158'. A forward stroke of the indexing arm 103 from the FIG. 4 position to the FIG. 5 position will therefore turn the ring W one step and thereby bring its number 1 embossing digit into the embossing station.

During the last phase of the first forward stroke of the indexing arm, that is, while the arm moves from the line 142 position of FIG. 18 to the line 143 position, the solenoid coil S1A of the valve W-3 is de-energized and at the same time, the coil S1B of the valve W-3 is ener-

gized with the result that the driving connection between the indexing arm and the ring W will be interrupted and the locking connection between the subframe and the ring W will be established.

The indexing arm will then start its return stroke from the FIG. 19 position and while it moves from the line 144 position of FIG. 19 to the line 146 position, the solenoid coil S1B of the valve W-3 will be de-energized and at the same time the coil S1A of the W-3 valve will be re-energized. As a result, the driving connection between the indexing arm and the W ring will be re-established and the locking connection between the W-ring and the subframe will be interrupted so that the indexing arm may move through another forward stroke and thereby bring the number 2 embossing digit of the W ring into the embossing station.

The described step by step advancement of the W-ring will automatically repeat itself in endless succession as long as the driving motor 124 is kept running. However, when the indexing arm 103 moves through the last phase of its ninth return stroke and its driving connection with the W ring will be re-established, the indexing arm will at the same time be coupled to the X ring so that the subsequent forward stroke of the indexing arm will advance not only the W ring but also the X ring one step, and the embossing digit combination will then be 0-010. Such simultaneous advance of the rings W and X by the tenth advance stroke of the indexing arm is obtained by the transmission of an energizing signal simultaneously to the solenoid coil S1A of the valve W-3 and to the solenoid coil S2A of the valve X-3.

The energizing signal which causes the valve X-3 to couple the indexing arm 103 to the ring X at the end of the ninth return stroke of the indexing arm is produced by a counting switch 3LS (FIG. 14) which is mounted on the subframe 102 below the decimal ring W. The counting switch 3LS has an actuating arm 186 (FIG. 16) which is spring biased to urge a roller 187 on the arm 186 against the underside of the ring W. A notch 188 at the underside of the ring W permits the switch 3LS to close when the number 9 digit of the W ring moves into the embossing station. The switch 3LS opens when the cipher digit of the W ring moves into the embossing station and remains open during each successive step of the ring W until the number 9 digit of the ring W again moves into the embossing station. The second closure of the 3LS switch causes the ring X to advance one step bringing the number 2 digit of the ring X into the embossing station. Continuous step by step advancement of the ring W thus causes the ring X to advance one step after each full revolution of the ring W.

Additional counting switches 4LS and 5LS (FIG. 14) corresponding to the counting switch 3LS are mounted on the subframe 102 below the rings W and Y, respectively. The ring X has a notch like the notch 188 of the ring W, which causes the switch 4LS to close after each full revolution of the ring X; and the ring Y has a similar notch which causes the switch 5LS to close after each full revolution of the ring Y. As will be explained more fully hereinbelow with reference to FIG. 20, switches 3LS, 4LS and 5LS are wired into the control circuit for the solenoid valves W-3, X-3, Y-3 and Z-3 in such a manner that continuous rotation of the countershaft 128 will automatically advance the embossing digit configuration of the device step by step from

0-000 to 9-999. The electric control circuit for the solenoid valves W-3, X-3, Y-3 and Z-3 also includes provisions for selectively establishing any desired readout by operation of the indexing arm, as will be explained more fully hereinbelow.

In addition to the radially concentric assembly of relatively rotatable decimal rings W, X, Y, Z, prefix embossing characters A, A (FIG. 4) are provided at the embossing station adjacent the inner periphery of the decimal ring Z. As shown in FIGS. 8 and 9, a pillow block 196 having rectangular pockets 197 and 195 is secured to the platform 173 of the subframe 102 by four cap screws 198, a spacer block 199 (FIG. 9) being interposed between the platform 173 and the pillow block 196. The embossing characters A are formed in relief on type blocks 201 and 202, which are removably fitted into the pockets 197 and 195, respectively. As shown in FIGS. 4 and 5, another pillow block 203 having rectangular pockets 204, 205, 206 may be provided on the subframe 102 at the embossing station adjacent the outer periphery of the decimal ring W. Type blocks bearing suffix embossing characters (not shown) may be removably fitted into the pockets 204-206, if desired.

As shown in FIGS. 1 and 2, the ram 3 of the embossing press 2 is provided at its lower end with a platen 17, and a flat rectangular pad 18 of elastically deformable material, such as Urethane, is secured to the underside of the platen 17. While the ram 3 is in the raised non-embossing position in which it is shown in FIGS. 1 and 18, the subframe 102 may be adjusted from its FIG. 1 position to its FIG. 2 position by rotation of the handwheel 106, and such adjustment of the subframe 102 places the embossing station of the subframe into cooperative relation with the pad 18 on the press ram 3. A strip of sheet material 19 of sufficient width to span the digit configuration of the decimal rings and any prefix and suffix embossing characters at the embossing station extends through the gap between the pad 18 and the underlying embossing station of the subframe. A down stroke of the press ram 3 from its FIG. 18 position to its FIG. 19 position will then emboss the digit configuration of the decimal rings and any prefix and suffix characters at the embossing station upon the sheet material strip 19.

The embossing stroke of the press ram 3 is initiated, as will be explained in detail hereinbelow, by the press control solenoid valve 9 (FIG. 18) whose coil is energized at, or substantially at the moment the indexing arm begins its return stroke from the FIG. 19 position to the FIG. 18 position. During the ensuing time interval in which the indexing arm swings from its FIG. 19 to its FIG. 18 position the press ram 3 is held momentarily in its embossing position, and during the same time interval all the embossing rings are secured against rotation by the projected lock bolts 158', 147', 159' and 160' (FIG. 7) and all the clutch pins 158, 147, 159 and 160 are retracted. Before the indexing arm completes its return stroke from the FIG. 5 position to the FIG. 4 position the coil of the press control solenoid valve 9 is automatically de-energized, and as a result the press ram 3 will have moved upward to a non-embossing position at, or substantially at the moment, the indexing arm arrives at the end of its return stroke from the FIG. 5 to the FIG. 4 position. During the ensuing time interval in which the indexing arm moves from its FIG. 4 to its FIG. 5 position, the press control valve

9 remains de-energized so that the press ram 3 will remain in its raised non-embossing position (FIG. 18) while the indexing arm moves from its FIG. 4 to its FIG. 5 position and causes relative rotation of the decimal rings as has been explained hereinbefore.

During each time interval between successive return strokes of the indexing arm the strip of sheet material 19 is automatically advanced a predetermined distance corresponding to the height of the automobile license plate to be produced. To that end auxiliary equipment, not shown, is provided and operated in timed relation to the press ram 3. Reference may be had to our pending U.S. application Ser. No. 461,721 filed on Apr. 17, 1974 for a fuller disclosure of such auxiliary equipment and other apparatus by which the embossed sheet material strip 19 is processed into complete, consecutively numbered automobile license plates.

The control system whereby the press ram 3 is moved into and out of its embossing position during each time interval between successive forward strokes of the indexing arm 103 is actuated by the counter shaft 128 (FIG. 7) of the drive mechanism 104 (FIG. 6) for the indexing arm 103.

The counter shaft 128 as shown in FIG. 17 and as explained hereinbefore is eccentrically connected with the indexing arm 103 so that 1 full revolution of the counter shaft causes a 36° forward stroke and a 36° return stroke of the indexing arm. In addition to this eccentric driving connection with the indexing arm, the counter shaft 128 has a chain and sprocket connection with a rotary switch unit RCS (FIG. 6) on the subframe 102. The switch unit RCS is of a type well known in the art and more particularly of the type shown in U.S. Pat. No. 3,120,595 issued on Feb. 4, 1964 to G. H. Cork et al for "Adjustable Rotary Switch." Briefly, the switch unit RCS comprises a vertical assembly of limit switches and associated actuating cams which are mounted on a rotary shaft 190 for rotation in unison therewith. Chain sprockets 191 and 192 of equal pitch diameters are keyed, respectively, to the shafts 128 and 190, and a roller chain 193 is trained around the sprockets 191 and 192 so as to connect the counter shaft 128 in a 1:1 driving connection with the switch shaft 190.

The rotary switch unit RCS, as diagrammatically shown in FIG. 17 includes two cam operated limit switches 1CS and 2CS which in turn are incorporated in an electrical control circuit for the solenoid valves W-3, X-3, Y-3 and Z-3 as shown in detail in FIG. 20. A third cam operated limit switch 3CS of the rotary switch unit RCS is wired into the control circuit for the press solenoid valve 9 as will be explained more fully hereinbelow.

Generally, the control circuit of FIG. 20 comprises a manually operable two-position mode selector switch 5SS which enables operation of the mechanism for rotating the decimal rings W, X, Y, Z either in the automatic mode or in the manual mode. Switch 5SS is shown in FIG. 20 as positioned in the automatic mode in which the advance of the rings W, X, Y, Z is automatically effected in progressive sequence in response to operation of the rotating cam switch assembly RCS. In its manual mode position, switch 5SS enables each ring W, X, Y, Z to be advanced individually to a desired position by manual operation of appropriate ring advance pushbutton switches PB1 (for ring W), PB3 (for ring X), PB4 (for ring Y), PB5 (for ring Z).

FIGS. 18 and 19 show the switches 5SS and PB1, PB3, PB4, PB5 as physically located on an operator's control panel CP. For convenience, certain relay coils and their associated relay contacts are designated in FIG. 20 by the same reference numerals.

As FIGS. 17, 18, 19 and 20 show, cam switch 1CS of the rotating cam switch assembly RCS, is effective, when operation of the ring turning mechanism is in the automatic count mode, to initiate operation of the clutch units W-1, X-1, Y-1, Z-1 and lock units W-2, X-2, Y-2 and Z-2, and consequent advancement of an appropriate ring or rings, and the cam switch 2CS effects operation of the clutch and lock units and consequent locking of the advanced ring or rings preparatory to a return stroke of indexing arm 3.

In operation, cam switch 1CS closes to energize relay coils R1 and R2 having hereinafter described contacts which operate, as hereinafter described, to enable the ring operated counting switches 3LS, 4LS, 5LS, if and when actuated closed by a respective ring W, X, Y, to operate the counting relays R5, R6, R7, respectively. In the automatic mode, the counting relay R4 operates directly in response to energization of relay coil R1 and closure of its relay contact R1A. In the manual mode, the counting relay R4 operates in response to manual closure of pushbutton switch PB1 (relay contact R 28 being closed when manual select relay coil R28 is energized by closure of selector switch contact 5SS1). Operation of the counting relays R4, R5, R6, R7 effects operation of the clutch unit relays CR4, CR1, CR2, CR3, respectively, and the lock unit relays CR4A, CR1A, CR2A, CR3A, respectively. Operation of the clutch unit relays CR4, CR1, CR2, CR3, in turn, effects operation of the clutch unit solenoid coils S1A, S2A, S3A, S4A, respectively. Operation of the lock unit relays CR4A, CR1A, CR2A, CR3A, in turn effects operation of the lock unit solenoid coils S1B, S2B, S3B, S4B, respectively. The clutch unit and lock unit solenoid coils, in turn, operate the solenoid valves W-3, X-3, Y-3, Z-3 for the clutch units W-1, X-1, Y-1, Z-1 and the lock units W-2, X-2, Y-2, Z-2.

In actual construction, the cams of the limit switches 1CS, 2CS and 3CS are mounted on the shaft 190 of the rotary switch unit RCS as shown in FIG. 17. For purposes of simplification, FIGS. 18, 19 and 20 show the cams 1CS, 2CS and 3CS aligned on a broken line RCS which represents the countershaft 128 in FIG. 17 and which, as mentioned before, has a 1:1 driving connection with the shaft 190 of the rotary switch unit RCS. As FIG. 20 shows, the cam slots or depressions in the cams 1CS and 2CS (which cam slots each subtend an angle of about 30° are 180° out of phase and the cam slot in cam 3CS which is in phase with that of cam 1CS subtends an angle of about 60°, so as to enable cam switch 3CS to remain closed long enough for an embossing stroke of the press cam 3. Cams 1CS, 2CS, 3CS operate cam switches 1CS, 2CS, 3CS, respectively. Cam switch 1CS closes just before indexing arm 103 is at the starting point of its cycle, i.e., just before it starts its forward stroke. Switch 1CS remains closed for a short period after the forward stroke has begun. The operating cam for the switch 2CS on the other hand, is angularly fixed on the shaft 190 in such a position that it closes just before indexing arm 103 reaches the mid-point of its cycle, i.e., just before the end of its forward stroke, and remains closed for a short period after the return stroke has begun.

Cam switch 3CS also closes before indexing arm 103 reaches the mid-point of its cycle and also remains closed for a period after the indexing arm commences its return stroke and of course, closes and remains closed for a longer period than cam switch 2CS.

The clutch unit solenoid coils S1A, S2A, S3A, S4A and the lock unit solenoid coils S1B, S2B, S3B, S4B are energizable from a source of 125 volt alternating current comprising supply lines AL1 and AL2. The clutch unit solenoid coils S1A, S2A, S3A, S4A are connected across the lines AL1 and AL2 in series with normally open clutch unit relay contacts CR4, CR1, CR2, CR3, respectively. The latter contacts are operated by clutch unit relay coils CR4, CR1, CR2, CR3, respectively, which are energizable from a source of 24 volt direct current comprising terminals DL1 and DL2. The lock unit solenoid coils S1B, S2B, S3B, S4B are also connected across the lines AL1 and AL2 in series with normally closed lock unit relay contacts CR4A, CR1A, CR2A, CR3A, respectively. The latter contacts are operated by lock unit relay coils CR4A, CR1A, CR2A, CR3A, respectively, which are energizable from the terminals DL1 and DL2. In practice, it is preferred that a clutch unit relay be physically associated with its corresponding lock unit relay to insure the previously mentioned seesaw action and this is indicated by dashed lines in FIG. 20.

The clutch unit relay coil CR3 is connected across terminals DL1 and DL2 in series circuit with a normally open counting relay contact R7A, a (shown closed) ring advance pushbutton contact PB5B, a normally open counting relay contact R6A, a (shown closed) ring advance pushbutton contact PB4B, and a normally open counting relay contact R5A.

The clutch unit relay coil CR2 is connected between terminal DL1 and a point between contacts PB5B and R6A. The clutch unit relay coil CR1 is connected between terminal DL1 and a point between contacts PB4A and R6A. The remaining relay coils CR1A, CR2A, CR3A and CR4A are connected across lines DL1 and DL2 in series with the counting relay contacts R5B, R6B, R7B, and R4B, respectively, which are all normally closed contacts.

The counting relay coils R4, R5, R6, and R7 are energizable from the direct current terminals DL1 and DL2. More specifically, the counting relay coils R5, R6, R7 are connected between terminals DL1 and DL2 in series with the normally open counting switches 3LS, 4LS, 5LS, hereinbefore described, and the closed contacts 5SS8, 5SS6, 5SS5 of the two-position count mode selector switch 5SS, shown as disposed in the automatic count mode. The counting relay coils R5, R6, R7 are alternately connectable during manual mode operation to terminal DL2 through the normally open manual advance pushbutton switches PB3, PB4, PB5, respectively, which are in series with the open contacts 5SS7, 5SS5, 5SS3, respectively, of count mode selector switch 5SS.

In the automatic mode, the counting relay coil R4 is connected between terminals DL1 and DL2 in series with the normally open relay contact R1A and the closed contact 5SS2 of selector switch 5SS. In the manual mode, coil R4 is connectable in series between terminals DL1 and DL2 through normally open manual counting pushbutton switch PB1 and normally open manual select relay contact R28. The manual select relay coil R28 for operating relay contact R28 is con-

nected between terminals DL1 and DL2 in series with the contact 5SS1 of count mode selector switch 5SS.

One side of relay coils R5, R6, R7 is alternately connectable to terminal DL2, (through normally closed relay contact R3C) through the relay holding contacts R5C, R6C, R7C, respectively.

The control circuit shown in FIG. 20 operates as follows. Assume that the lines AL1 and AL2 and DL1 and DL2 are energized and that all contacts are initially in the condition shown in FIG. 20. Further assume that indexing arm 103 is undergoing its oscillating motion as hereinbefore described. Also assume that the clutch unit relay coils CR1, CR2, CR3, CR4 are de-energized (because the relay contacts R4A, R5A, R6A, R7A are open) and that the lock unit relay coils CR1A, CR2A, CR3A, CR4A are energized (because the relay contacts R4B, R5B, R6B, R7B are closed).

If manual operation is desired, selector switch 5SS is moved to its manual position thereby closing its contacts 5SS1, 5SS3, 5SS5, 5SS7 and opening its contacts 5SS2, 5SS4, 5SS6, 5SS8, and 5SS9. In this condition, manual closure of the pushbutton switches PB1, PB3, PB4, or PB5 effects energization of the relay coils R4, R5, R6 or R7, respectively, and this in turn, effects energization of the clutch unit relay coils CR4, CR1, CR2, or CR3, respectively, and de-energization of the lock unit relay coils CR4A, CR1A, CR2A, or CR3A, respectively, and of the press control solenoid 9. Energization of a clutch unit relay coil and de-energization of its corresponding lock unit relay coil effects energization of a corresponding clutch unit solenoid coil (S1A, S2A, S3A, S4A) and de-energization of a corresponding lock unit solenoid coil (S1B, S2B, S3B, S4B) and this, in turn, effects operation of a corresponding solenoid valve W-3, X-3, Y-3, Z-3 for the rings W, X, Y, Z, as hereinbefore explained.

If automatic operation is desired, selector switch 5SS is moved to its automatic position shown in FIG. 20 thereby closing its contacts 5SS2, 5SS4, 5SS6, 5SS8, and 5SS9 and opening its contacts 5SS1, 5SS3, 5SS5, 5SS7. In this condition of switch 5SS, the manual pushbutton switches PB1, PB3, PB4, PB5 are rendered ineffective and ring advance depends on the operation of cam switches 1CS and 2CS and the counting switches 3LS, 4LS, 5LS. More specifically, as cam 1CS rotates to close cam switch 1CS (as arm 3 approaches its start of forward stroke position), relay coil R1 is energized and closes its contact R1A (to energize relay coil R4) and closes its contact R1B (to energize relay coil R2).

When relay coil R4 is energized, it closes its holding contact R4C and its relay contact R4A (to energize clutch unit relay coil CR4 and thereby enable ring W to advance) and opens its relay contact R4B (to de-energize lock unit relay coil CR4A and thereby unlock ring W so it can advance). When relay coil R2 is energized it closes its relay contact R2A (to hold coil R2 energized) and opens its relay contact R2B (to insure de-energization of relay coil R3). As cam 1CS rotates to a position wherein cam switch 1CS opens, the indexing arm 103 has advanced the ring W through an angle of substantially 36° and the clutch pin 158 is withdrawn and the lock pin 158' is projected in a hole 161 in ring W. When cam 2CS rotates to a position wherein it closes cam switch 2CS (i.e., as arm 103 approaches the end of the forward stroke), relay coil R3 is energized and opens its contact R3A (to insure de-energization of relay coil R2), closes its holding contact R3B, and

opens its relay contact R3C (to disable the counting switches 3LS, 4LS, 5LS). This process is repeated until, during the tenth advancing step of ring W, the counting switch 3LS closes to energize relay coil R5.

When relay coil R5 is energized it closes its holding contact R5C, closes its contact R5A (to energize clutch unit solenoid relay coil CR1) and opens its contact R5B (to de-energize locking unit solenoid relay coil CR1A). The relay coils CR1 and CR1A then operate respectively to close the relay contact CR1 and open the relay contact CR1A, whereby the ring X advances. Cam switches 1CS and 2CS operate repeatedly as hereinbefore described and ring X is repeatedly advanced until, during its tenth step, the counting switch 4LS closes to energize relay coil R6.

When relay coil R6 is energized it closes its holding contact R6C, closes its contact R6A (to energize clutch unit solenoid relay coil CR2) and opens its contact R6B (to de-energize locking unit solenoid relay coil CR2A).

20 The relay coils CR2 and CR2A then operate respectively to close the relay contacts CR2 and open the relay contact CR2A, whereby ring Y is advanced. Cam switches 1CS and 2CS operate successively as hereinbefore described and ring Y is repeatedly advanced until, during its tenth step, the counting switch 5LS closes to energize relay coil R7.

When relay coil R7 is energized it closes its holding contact R7C, closes its contact R7A (to energize clutch unit solenoid relay coil CR3) and opens its contact R7B (to de-energize locking unit solenoid relay coil CR3A).

25 The relay coils CR3 and CR3A then operate respectively to close the relay contact CR3 and open the relay contact CR3A, whereby ring Z advances. Cam switches 1CS and 2CS operate successively as hereinbefore described and ring Z is advanced step by step until, after its tenth step, and after the rings W, X, Y have rotated a sufficient number of times the combination of digits available (i.e., 9-999) is exhausted. The prefix and or suffix embossing characters may then be changed and

30 a new production run may be started. Individual rotation of the decimal rings independently of each other as described hereinbefore with reference to selector switch 5SS and the pushbutton switches PB1, PB3, PB4, and PB5 provides for adjustment of the decimal ring assembly to any desired embossing digit configuration preparatory to start of a production run.

SUMMARY

The rotary switch unit RSC and associated relays R1 to R7 together with the solenoid operated valves 9 and W-3, X-3, Y-3, Z-3 virtually provide a system of operatively interrelated control means for the clutch units W-1, X-1, Y-1, Z-1, for the embossing ram 3 and for the lock units W-2, X-2, Y-2 and Z-2 which is responsive to the forward and reverse strokes of the indexing arm 103, whereby all of the embossing rings W, X, Y, Z are locked against rotation and the ram is reciprocated between its non-embossing and embossing positions during successive reverse strokes of the indexing arm, and whereby the embossing rings are selectively released and rotated step by step in predetermined order during successive forward strokes of the indexing arm while the embossing ram is held in its non-embossing position.

65 We claim:

1. An embossing press comprising a frame, a ram reciprocably mounted on said frame for back and forth

movement between a non-embossing and an embossing position; an assembly of embossing rings mounted on said frame in cooperative relation to said ram and for relative rotation on a common axis; an indexing arm pivoted on said frame coaxially with said ring assembly; oscillating means for alternately effecting forward and reverse strokes of said indexing arm on its pivot axis; selectively engageable and disengageable torque transmitting means operatively interposed between said indexing arm and said embossing rings; and operatively interrelated control means for said torque transmitting means and for said ram responsive to said forward and reverse strokes of said indexing arm whereby said rings are rotated step by step in predetermined order upon successive forward strokes of said indexing arm and left in indexed positions during said reverse strokes of said indexing arm, and whereby said ram is held in said non-embossing position during said forward strokes of said indexing arm and reciprocated between said non-embossing and embossing positions during said reverse strokes of said indexing arm.

2. An embossing press comprising a frame, a hydraulic power unit and an associated reciprocable embossing ram operatively mounted on said frame; solenoid operated valve means connected to said power unit for effecting back and forth movement of said ram between a non-embossing and an embossing position; an assembly of embossing rings mounted on said frame in cooperative relation to said ram and for relative rotation on a common axis, an indexing arm pivoted on said frame coaxially with said ring assembly; oscillating means for alternately effecting forward and reverse strokes of said indexing arm on its pivot axis; alternately expandable and contractable cylinder units mounted on said indexing arm in engageable and disengageable relation, respectively, to said embossing rings; fluid conduit means and associated solenoid operated valve means connected with said cylinder units for selectively establishing and interrupting torque transmitting connections between said indexing arm and said embossing rings; and operatively interrelated electrical control means for said solenoid operated valve means of said cylinder units and for said solenoid operated valve means of said power unit responsive to said forward and reverse strokes of said indexing arm whereby said embossing rings are rotated step by step in predetermined order upon successive forward strokes of said

indexing arm and left in indexed positions during said reverse strokes of said indexing arm, and whereby said ram is held in said non-embossing position during said forward strokes of said indexing arm and reciprocated between said non-embossing and embossing positions during said reverse strokes of said indexing arm.

3. An embossing press as set forth in claim 2, wherein said oscillating means comprise a rotary drive shaft journaled on said frame and a connecting rod having eccentric pivot connections at its opposite ends, respectively with said drive shaft and with said indexing arm; and wherein said electrical control means comprise first and second electrical switches and actuating cams therefor rotatable in unison with said drive shaft for controlling said solenoid operated valve means of said cylinder units, and a third electrical switch and an actuating cam therefor rotatable in unison with said drive shaft for controlling said solenoid operated valve means of said power unit.

4. An embossing press comprising a frame, a ram reciprocably mounted on said frame for back and forth movement between a non-embossing and an embossing position; an assembly of embossing rings mounted on said frame in cooperative relation to said ram and for relative rotation on a common axis; an indexing arm pivoted on said frame coaxially with said ring assembly; oscillating means for alternately effecting forward and reverse strokes of said indexing arm on its pivot axis; selectively engageable and disengageable torque transmitting means operatively interposed between said indexing arm and said embossing rings; selectively engageable and disengageable locking means operatively interposed between said frame and each of said embossing rings; and operatively interrelated control means for said torque transmitting means, for said locking means and for said ram responsive to said forward and reverse strokes of said indexing arm whereby all of said locking means are engaged and said ram is reciprocated between said non-embossing and embossing positions during said reverse strokes of said indexing arm, and whereby said locking means are selectively disengaged and said torque transmitting means are selectively engaged and operative to rotate said rings step by step in predetermined order upon successive forward strokes of said indexing arm while said ram is held in said non-embossing position.
